HOWARD J. MURRAY, OF BROOKLYN, NEW YORK, ASSIGNOR TO HENRY SIEBEN, OF HADLEY, NEW YORK

GAS CUT-OFF

Application filed November 30, 1926. Serial No. 151,818.

The invention relates in general to a gas cut-off of the type in which the valve is normally held in an open position and designed to be closed either by manual actuation from 5 a remote point or automatically through a rise in temperature in the vicinity of the mechanism.

In such devices heretofore known the mechanism for controlling the valve has ordinarily 10 been mounted in an exposed position or in a casing separate from the casing which contains the valve, with the result that there has been provided structures which were not peculiarly adapted to meet the commercial 15 requirements of a small, compact marketable unit which could be contained in the confined and small available spaces where local fire and building regulations require the installation of such equipment.

Accordingly, one of the objects of the invention is to provide a neat, compact and easily constructed unit which will feature compactness, and at the same time permit ready access to the mechanism containing 25 compartment for inspection, resetting and repairs.

Broadly, this is attained by providing both the valve casing and the casing containing the controlling mechanism as a single casing 30 with one side of the mechanism casing exposed by the opening of a hinged cover.

In prior constructions it has been usual to provide separate mechanisms for releasing the spring controlled valve, one of which 35 mechanisms is manually actuated and the other released automatically by temperature controlled means, as for instance, by the melting of a fusible link. Such dual mechanism adds to the production cost and unnecessarily complicates the construction.

Another object of the present disclosure is to simplify such construction; to eliminate the usual duplication of releasing parts, and to hold the valve in open position against the 45 closing action of its controlling spring by a single restraining mechanism which can be released either manually, or automatically by the melting of a fusible link forming part of the restraining mechanism.

This phase of the invention is attained

broadly by securing the fusible link to a single valve controlling arm and in turn securing the fusible link in fixed position to the hooked end of a manually releasable latch or detent in the form of a lever in turn controlled by a pull member actuated from a point remote from the controlled mechanism.

The invention also features the utilization of a spiral spring which not only has the virtue of being extremely efficient in those positions where it must be held under tension for long periods of time, but also acts promptly and positively when released to secure the valve in closed position. This form of spring in the instant case is additionally advantageous in that it can be accommodated within a narrow space and thus assist in contributing to the compactness of the construction as a whole.

Various other objects and advantages of the invention will be in part obvious from an inspection of the accompanying drawings and in part will be more fully set forth in the following particular description of one form of device embodying the invention, and the invention also consists in certain new and novel features of construction and combination of parts hereinafter set forth and claimed.

In the accompanying drawing:

Fig. 1 is a view in side elevation of a gas cut-off constituting a preferred embodiment of the invention;

Fig. 2 is an end view looking at the right hand side of the disclosure in Fig. 1 and showing the mechanism containing casing in vertical axial section and taken on the line 2-2 of Fig. 3; and

Fig. 3 is a view in side elevation looking at the right hand side of the showing in Fig. 2 and with the cover plate in open position.

In the disclosure there is shown a single unitary casting forming a valve casing 10 of somewhat conventional form and a mechanism containing casing 11 with a common wall 12 dividing the valve containing casing 10 from the compartment 13 in the casing 11 containing the valve actuating mechanism hereinafter described. A valve 14 in the casing 10 is mounted on a valve stem 15 which

extends through the wall 12 and is intruded into the chamber 13.

The mechanism casing 11 is in the form of a flat cylinder with the side opposite the wall 12 entirely open so as to permit ready access to the chamber 13 and its contained mechanism. The open side of the casing is normally closed by a cover 16 provided with air vents 17 and is hingedly connected on pivot pin 18 to one side edge of the casing 11. The casing 11 and cover 16 are provided with apertured lugs 19 and 20 respectively which when the cover is in closed position are adapted to be engaged by some suitable form of sealing lock 21.

The intruded portion of the stem 15 is provided with a single valve actuating arm 22 which extends radially of the casing 11. To a pin 23 on the arm is secured one end of a coiled spiral spring 24, the opposite end of which is secured to a pin 25 projecting from the wall 12. This spring when released reacts on the valve to close the same firmly onto its seat and thus intercept the gas flow through the casing 10 as is usual in such constructions. To the free end of the arm 22 is pivotally connected one end of a replaceable fusible link 26, the other end of which terminates in an eye 27. The eye is engaged by the hook end 28 of a tripping lever 29 pivotally mounted on fulcrum pin 30 secured to the wall 12. The opposite end of the lever is provided with an eye 31 to which is engaged a pull rod 32 extending through an aperture in the side of the casing 11. The eye 27 normally rests upon a stop pin 33 which acts to prevent the same from downward movement while the hook end 28 is being withdrawn from its eye.

In operation it will be understood that the valve is set in open position by manually rotating the arm 22 anticlockwise and inserting the eye 27 over the hook end of the tripping lever after which the cover is closed and the device is in condition to be actuated. A pull on the rod 32 causes the lever to swing about its fulcrum and thus withdraw the hook end from the eye end of the fusible link. The spring 24 is thus permitted to act through the valve arm to seat the valve in its closed position.

In the absence of this manual actuation the valve arm can be released by the melting of the fusible link. The melting of the link releases the arm and the spring acts thereon to close the valve without effect on the tripping lever. It is understood that the valve may be released for closing movement repeatedly by the manual actuation without injuring the fusible link and the fusible link is destroyed only when melted. In this case a new link may take the place of the destroyed link as is usual in replacing fusible links in devices of this character.

By means of a device of the character illus-

trated it is possible to attain all of the advantages inherent in manually actuated and self releasing valves as has characterized known similar constructions and the present disclosure has the advantage in that both the manual release and the fusible link are contained as a single linkage acting on the valve arm to hold the same in open position.

The structure is commercially perfected in that the containing casings can be formed of a single casting and the valve closing mechanism is protected both from the gas flow in the valve casing and from unauthorized tampering and yet is readily accessible to authorized parties for inspection, repairs and resetting of a damaged fuse. The flat coiled spring permits the use of a long spring and at the same time confines it to a limited space concentrically of the valve stem and exposed to an air cooling through the vents in the perforated cover.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a cut-off, the combination of a single casting including a valve casing, and a mechanism containing casing integral with the valve casing and provided with an open side, said casings provided with a common wall, a valve contained in the valve casing and provided with a valve stem extending through said common wall and protruding into the mechanism containing casing, a spring in said mechanism containing casing tending to move the valve to closed position, mechanism housed in said mechanism containing casing normally acting on the stem to hold the valve in open position and responsive to a rise in temperature and to a manual actuation for releasing the stem from said holding mechanism to permit the valve to be moved to closed position by said spring and a cover for said open side adapted to be moved into open position to expose said spring and mechanism.

2. A valve controlling mechanism including a valve stem provided with a single actuating arm, a valve having means actuated by said stem for lifting the valve to closed position, means engaging the arm to hold the same normally in preset position, said means including a tripping hook and a fusible link having one end secured to the hook and the other end secured to the arm and a manually actuated member secured to the hook to trip the hook out of holding engagement with the fusible link and thus release the arm and fusible link by manual

operation and said link capable when fused of automatically releasing the arm independently of the manually actuated hook and a spring acting on said arm to close the valve 5 when the arm is released.

3. A valve controlling mechanism including a valve stem provided with a single actuating arm, means engaging the arm to hold the same normally in preset position, said means 10 including a tripping hook and a fusible link having one end secured to the hook and the other end secured to the arm and a manually actuated member secured to the hook to trip the same out of holding engagement with the 15 fusible link and thus release the arm and fusible link by manual operation and said link capable when fused of automatically releasing the arm independently of the manually actuated hook, and a spring normally 20 acting on the arm and tending to move the same and thus turn the valve stem when said holding means is released.

4. In a cut-off, the combination of a normally open gas flow controlling valve normally hanging in a depending position, valve controlling means including a valve arm, a fusible link secured to the free end of said arm, a pivotally mounted tripping hook engaging the link for holding the arm and thus holding the valve in preset position and a spring acting on the arm for elevating the valve into closed position when released by the tripping of the hook or by the melting of the link.

5. In a device of the class described, the combination of a valve casing, a valve therein provided with a valve stem, an arm having one end secured thereto and the other end free, a spring normally acting on the arm intermediate its ends to move the same in one direction, restraining means normally acting on the free end of the arm to hold the same in preset position, said restraining means including manually releasing mechanism carried by the valve casing, and automatic releasing means responsive to a rise of temperature of said restraining means.

6. In a gas shut-off, the combination of a flat cylindrical casing provided centrally thereof with a valve stem intruded into the same, a valve arm secured to the intruded end of said shaft, a flat spiral spring having one end secured to the casing and the other end to the arm adjacent its free end, and means exteriorly of the spring engaging the free end of the arm and normally acting to secure the stem from rotating under the influence of said spiral spring.

7. In a gas cut-off, the combination of a valve provided with a stem having an arm, a spring acting on said arm to move the valve, a single linkage secured at one end to a support and at its other end engaging the arm to hold the same from moving under the influence of said spring, said linkage including

manually actuated releasing means and automatically actuated releasing means responsive to a rise of temperature in said last named releasing means.

8. In a shut-off, the combination of a flat 70 cylindrical casing having a valve stem intruded axially into the same, a valve arm secured to the stem and extending radially of the casing, a flat spiral spring having one end secured to the casing, wrapped spirally about the stem and having its other end secured to the arm and manually and automatically releasable means for securing the arm against the tendency of said spring to rotate the valve stem.

9. In a device of the class described, the combination of a valve stem mounted for rotary movement and provided with a valve and an arm, a spring acting on the arm in spaced relation to the valve stem to exert a 80 leverage effect thereon, tending to rotate the same in a direction to move the valve on to its seat and acting on the closed valve to hold the same firmly in engagement with its seat, means for securing the valve in open position 85 against the tension of said spring, said means including a replaceable fusible link separable from the arm and having one end engaging said arm and the other end provided with an eye, and manually actuated means normally 90 supporting the eye-containing end of said link and adapted to release said end to permit the link to move with the spring actuated arm.

10. In a device of the class described, the 100 combination of a valve provided with a valve arm, means tending to move the valve arm in one direction and acting therethrough to move the valve on to its seat, means for securing said arm in position to hold the valve off its seat, said last named means including a manually releasable detent, a fusible link with one end secured to the arm and the other end engaging detent, and an abutment positioned to be engaged by the link to hold the 105 link while the detent is being released.

11. In a device of the class described, the combination of a valve stem mounted for rotary movement, an arm extending radially therefrom, means acting thereon and tending 115 to move the valve into closed position, means for releasably securing the arm in position to hold the valve in open position, said means including a manually releasable latch, and a long connector between the latch and arm, 120 said connector extending with its length substantially at a tangent to the circle of rotation of said arm and including a fusible part, and means to hold the connector in said tangential position while the latch is being released.

Signed at New York, in the county of New York and State of New York this fifth day of November, A. D. 1926.
